UNITED STATES PATENT OFFICE

98,534

DESIGN FOR A MOTION PICTURE FILM VIEWING MACHINE

Walter J. Lumbleau, Los Angeles, Calif.

Application April 19, 1935, Serial No. 56,464

Term of patent 3½ years

To all whom it may concern:

Be it known that I, Walter J. Lumbleau, a citizen of the United States, residing at Los Angeles, in the county of Los Angeles and State of California, have invented a new, original, and ornamental Design for a Motion Picture Film Viewing Machine, of which the following is a specification, reference being had to the accompanying drawing, forming a part thereof.

Fig. 1 is a side elevational view of a motion

picture film viewing machine, showing my new design; and

Fig. 2 is a front elevation of the same the opposite side of the film viewing machine being of the same design as shown in Fig. 1.

I claim:

The ornamental design for a motion picture film viewing machine, as shown and described.

WALTER J. LUMBLEAU.
